UNITED STATES PATENT OFFICE.

JAMES S. STEPHENS, OF CHICAGO, ILLINOIS.

DESIGN FOR A VEHICLE-BODY.

46,327.

Specification for Design.

Patented Aug. 25, 1914.

Application filed May 20, 1914. Serial No. 839,892. Term of patent 7 years.

To all whom it may concern:

Be it known that I, JAMES S. STEPHENS, a citizen of the United States of America, and a resident of Chicago, in the county of Cook and State of Illinois, with a post-office address at 7321 Bond avenue, in said Chicago, have invented a new, original, and ornamental Design for Vehicle-Bodies, of which the following is a specification, reference being had to the accompanying drawings, forming part thereof.

Figure 1 is a plan view of a vehicle body

showing the new design. Fig. 2 is a front view. Fig. 3 is a perspective view of the side of the vehicle body. Fig. 4 is a perspective view showing the side and rear of the vehicle body.

I claim:

The ornamental design for a vehicle body substantially as shown.

JAMES S. STEPHENS.
